UNITED STATES PATENT OFFICE

EDMUND ALTENKIRCH, OF ALT-LANDSBERG-SUD, GERMANY, ASSIGNOR TO SIEMENS-SCHUCKERTWERKE GESELLSCHAFT MIT BESCHRANKTER HAFTUNG, OF SIEMENS-STADT, NEAR BERLIN, GERMANY, A CORPORATION OF GERMANY

APPARATUS FOR BOILING LIQUIDS

Application filed June 1, 1925, Serial No. 34,051, and in Germany June 3, 1924.

My invention relates to improvements in apparatus for boiling liquids. In boiling liquids which should not be completely evaporated but part of which only should 5 at first be converted into vapor, it is frequently advisable to pass the liquid in a uniform stream through the boiling chamber. It is already known to obtain the necessary motion of the liquid without the application 10 of any special circulating apparatus by passing the liquid together with the vapor developed through an ascending pipe. The vapor bubbles rising in this pipe carry the liquid along and at the rate at which it is 15 discharged at the top of the ascending pipe it enters the pipe at the bottom.

According to my invention a particularly uniform boiling of the water is attained by providing the ascending pipe with traps for 20 the steam. Such a device is particularly advantageous for such liquids which show a considerable retardation of boiling. The rising pipe may be heated from the outside in order that it may itself serve as boiling 25 chamber.

The drawing affixed to my specification and forming part thereof shows a number of embodiments of my invention.

Fig. 1 is a vertical section through a 30 simple plant,

Fig. 2 another construction of boiler and

Fig. 3 a plant for dehydrating diluted sulphuric acid embodying my invention.

Referring to Fig. 1 the liquid to be boiled 35 is contained in a storage tank 1 which communicates with a coil 2. This coil is located in a heating chamber 3 into which heating gases enter at 4 and escape at 5. When the boiling process starts the level of the liquid 40 in the coil 2 is at the same height as the level of the liquid in the tank 1. As soon as the water in the coil 2 starts boiling the steam bubbles generated drive the liquid in front of them. The liquid is in this way conveyed 45 into the tank 10 from which the steam is able to escape through the outlet pipe 6. According to my invention the coil 2 is provided with trapping chambers 7, 8, 9 in which the steam, or generally speaking the vapor, is 50 caught. Practical experience has proved

that these traps have a decisive influence upon the boiling process and render it more uniform, an advantage which is the more pronounced the greater is the retardation of boiling of the liquid. If, for instance, vapor 55 is to be expelled from diluted sulphuric acid by heating, a considerable amount of super-heating is necessary. The boiling then starts so suddenly and with such violence that the liquid is not only ejected at the top of the 60 pipe 2 but also at the bottom. When cold liquid enters the pipe 2 from the tank 1 the boiling would cease in a smooth uniformly 65 ascending pipe until the next boiling surge occurs. A uniform boiling process and a uniform stream of liquid through the pipe 2 upwards into the receiver 10 could not possibly take place under these circumstances.

If, however, according to my invention vapor is trapped in the chambers or spaces 7, 70 8, 9, the retardation of boiling will obviously be suppressed at the points of contact between vapor and liquid. In any case it can be clearly observed that at the places where vapor has been trapped a continuous surge- 75 free development of vapor takes place. The ascending steam bubbles carry the liquid in the pipe along in a uniform stream and the boiling takes a quiet and steady course assuming a sufficient supply of heat. If it is 80 desired that the same liquid be subjected to the boiling process a number of times, it is only necessary to return the liquid by a connecting pipe from the vessel 10 back into the tank 1. Some of the vapor trapping 85 chambers may be of spherical shape as at 7 others may consist simply of cavities such as at 8 and 9.

A further modification of the invention is 90 illustrated in Fig. 2. The boiling pipe 12 is in this case led upwards in one plane but bent in sine wave fashion so that upwardly directed portions alternate with downwardly directed portions. At the places 17, 18, 19, 20 at which the pipe turns downwards steam 95 bubbles remain stationary when the boiling liquid passes along the pipe and ensure a steady progress of the boiling operation as specified with reference to Fig. 1. At the turning point 17 no vapor collects if the liquid 100

has up to then not attained a sufficiently high temperature. The pipe 12 is housed in a heating chamber 13 into which the heating gases enter at 14 and from which they escape 5 at 15. The boiling liquid is discharged into a tank 22 and supplied from a storage tank 21.

Boiling apparatus of this kind is particularly suitable for expelling water from diluted sulphuric acid, for concentrating salt 10 solutions and many other purposes.

In Fig. 3 the application of my invention for the dehydration of diluted sulphuric acid for the operation of an absorption refrigerating machine is illustrated. The low temperature is generated in an evaporator 31 by evaporating therein water at low pressure. The stream passes through a pipe 32 into an absorber 33 which is fed with a concentrated sulphuric acid solution by the pipe 34. The 15 steam is absorbed by the sulphuric acid in the absorber and the heat set free during the absorption is transferred to the surrounding atmosphere. For this purpose the absorber 33 is provided with radiator fins. The sulphuric acid solution diluted with water reaches the collecting vessel 35 and flows through the pipe 36 towards the lower end of the boiling pipe 37. This boiling tube is heated by an electric heating element 38. It is a 20 smooth spirally wound pipe the axis of which is disposed obliquely so that each turn of the coil consists of an upwardly directed portion and a downwardly directed portion. At the turning points between the two portions 25 steam is detained in the same manner as described with reference to Fig. 2 and thus a uniform generation of steam and supply of liquid ensured. The simple manner of manufacture of such a pipe and the large number 30 of trapping spaces renders this construction particularly valuable. The ascending mixture of steam and liquid reaches a gas separating chamber 39 from which the liquid is returned into the absorber 33 through the 35 pipes 40 and 34. The expelled steam accumulates in the steam dome 41 and is led into a condenser formed by a worm-shaped pipe 42 provided with radiation fins. The water condensed in this condenser ascends through the 40 pipe 43 into the evaporator and is here again 45 evaporated.

What I claim as my invention is:

1. An absorption machine having means for expelling the operating medium in vapour 50 form from the absorption liquid, comprising an ascending tubular element for raising the absorption liquid by the ascending medium vapour, means for heating said element to expel the operating medium, said tubular element having sections with suitably inclined wall portions for trapping some of the vapour bubbles in said sections, means for receiving the impoverished liquid discharged at the upper tube end, means for conducting away 55 the vapour expelled from the liquid, means for

bringing the operating medium and absorption liquid again into contact to form a solution, and means for conducting said solution to the lower end of said tubular element.

2. In a refrigerating system, the combination of a boiler for expelling a refrigerant as a gas from an absorption liquid upon the application of heat thereto, a chamber associated with the boiler adapted to receive the gaseous refrigerant and the absorption solution from the boiler and separate the same, an absorber for causing the absorption liquid to absorb the gaseous refrigerant expelled from the boiler, and conduits connecting the boiler, gas separating chamber and absorber 70 to form means for circulating the absorption solution therebetween, said boiler also functioning to cause circulation of the absorption solution and having means for preventing violent surges of the solution therein. 75

3. In a refrigerating system, an absorber, a gas separating chamber, conduits connecting the same to form means for circulating an absorption solution therethrough and a gas lift pump in one of said conduits operable 80 upon the application of heat thereto to cause the formation of bubbles in the solution to cause the same to rise, and said pump having means for preventing violent surges of the solution therein. 85

4. In a refrigerating system, a device for circulating an absorption solution and for expelling a refrigerant therefrom upon the application of heat thereto, said device consisting of a pipe of small diameter having portions arranged to cause the formation of gas pockets in said pipe to prevent violent surges of the solution therein. 90

5. In a refrigerating system, a device for circulating an absorption solution and for expelling a refrigerant therefrom upon the application of heat thereto, said device consisting of a coil of pipe of small diameter, the longitudinal axis of which is inclined with respect to the vertical whereby gas pockets are 100 formed in portions of the coil and facilitate uniform boiling of the solution without surges. 105

6. A device for circulating a solution and for expelling the solute therefrom comprising a pipe of small diameter adapted to cause bubbles formed therein to be interspersed between slugs of the solution to thereby cause the same to rise and having means for preventing violent surges of the solution therein. 110

7. In combination a device for circulating a solution and for expelling the solute therefrom comprising a pipe of small diameter adapted to cause gas bubbles formed therein to be interspersed between slugs of the solution and having means for preventing violent surges of the solution therein, a chamber associated with said device for receiving both the gas and the solution therefrom and for 115 120 125 130

causing the separation of same and a means for returning the solution to said device.

8. A circulatory system containing two mutually soluble liquids having different boiling points, said system comprising a heating section for circulating the liquids and for boiling the liquid of lower boiling point out of the other liquid, said heating section consisting of a conduit arranged in a non-horizontal position and a heating device associated therewith, said conduit having means therein for trapping vapors.

9. A circulatory system containing two mutually soluble liquids having different boiling points, said system comprising a heating section for circulating the liquids and for boiling the liquid of lower boiling point out of the other liquid, said heating section consisting of a conduit arranged in a non-horizontal position and a heating device associated therewith, said conduit having vapor traps distributed along the interior thereof.

10. A circulatory system containing two mutually soluble liquids having different boiling points, said system comprising a heating section for circulating the liquids and for boiling the liquid of lower boiling point out of the other liquid, a chamber adapted to receive the liquid and vapor from said heating section and to separate them, means for separately conveying away the liquid and vapor from said chamber, means for condensing the vapor, and means for bringing the condensate and the other liquid together and for conveying the resulting solution to said heating section, said heating section comprising a conduit arranged in a non-horizontal position and a heating device associated therewith, said conduit having means therein for trapping vapors.

11. An absorption system containing two fluids having different boiling points, the fluid having the higher boiling point being a liquid at all temperatures to which it is subjected in said system and being capable of absorbing the other fluid, said system comprising means for bringing said fluids into contact to produce a solution, a conduit arranged in a non-horizontal position, means for guiding said solution into the lower end of said conduit, means for heating said conduit to vaporize the fluid of lower boiling point and thereby cause an upward flow of the fluid in said conduit, said conduit having means therein for trapping vapor, and a chamber at the upper end of said conduit adapted to receive the fluids discharged therefrom and allow them to separate.

12. A device for separating into its constituents a solution of two fluids, at least one of which is a liquid, and which have different boiling points, said device comprising a conduit arranged in a non-horizontal position having an inlet at its lower end and an outlet at its upper end, means for feeding the solu-

tion to the inlet end of said conduit, means for heating the solution in said conduit to vaporize the fluid having the lower boiling point and to thereby cause the fluids in said conduit to ascend and be discharged through said outlet, means in said conduit for trapping vapor, and means for receiving the liquid discharged from said outlet.

13. A device for separating into its constituents a solution of two fluids, at least one of which is a liquid, and which have different boiling points, said device comprising a conduit arranged in a non-horizontal position having an inlet at its lower end and an outlet at its upper end, means for feeding the solution to the inlet end of said conduit, means for heating the solution in said conduit to vaporize the fluid having the lower boiling point and to thereby cause the fluids in said conduit to ascend and be discharged through said outlet, said conduit having sections with suitably downwardly inclined wall portions for trapping vapor.

14. A device for separating into its constituents a solution of two fluids, at least one of which is a liquid, and which have different boiling points, said device comprising a conduit arranged in a non-horizontal position having an inlet at its lower end and an outlet at its upper end, means for feeding the solution to the inlet end of said conduit, means for heating the solution in said conduit to vaporize the fluid having the lower boiling point and to thereby cause the fluids in said conduit to ascend and be discharged through said outlet, said conduit consisting of alternately upwardly and downwardly inclined sections forming vapor traps.

15. A device for separating into its constituents a solution of two fluids, at least one of which is a liquid, and which have different boiling points, said device comprising a conduit arranged in a non-horizontal position having an inlet at its lower end and an outlet at its upper end, means for feeding the solution to the inlet end of said conduit, means for heating the solution in said conduit to vaporize the fluid having the lower boiling point and to thereby cause the fluids in said conduit to ascend and be discharged through said outlet, said conduit consisting of a spiral tube upwardly inclined in its general direction, the inclination of the axis of the spiral being such that the spires of the tube form alternately upwardly and downwardly inclined sections forming vapor traps.

In testimony whereof I affix my signature.
EDMUND ALTENKIRCH.
